(57) **CLAIM**

The ornamental design for a label sheet, as shown and described.

DESCRIPTION

FIG. 1 is an enlarged front view of a first embodiment of a label for a label sheet;

FIG. 2 is a left side view of FIG. 1 thereof;

FIG. 3 is a top side view of FIG. 1 thereof;

FIG. 4 is an enlarged front view of a second embodiment of a label for a label sheet;

FIG. 5 is a left side view of FIG. 4 thereof;

FIG. 6 is a top side view of FIG. 4 thereof;

FIG. 7 is an enlarged front view of a fifth embodiment of a label for a label sheet;

FIG. 8 is a left side view of FIG. 7 thereof;

FIG. 9 is a top side view of FIG. 7 thereof;

FIG. 10 is an enlarged front view of a sixth embodiment of a label for a label sheet;

FIG. 11 is a left side view of FIG. 10 thereof; and,

FIG. 12 is a top side view of FIG. 10 thereof.

The broken lines in the figures are included for the purpose of illustrating portions of a label sheet assembly and form no part of the claimed design.

1 Claim, 4 Drawing Sheets
